UNITED STATES PATENT OFFICE.

MIKEL SCHULTZ, OF KAYLOR, PENNSYLVANIA.

DOUBLE-MOLDBOARD PLOW.

1,384,924.

Specification of Letters Patent. Patented July 19, 1921.

Application filed July 15, 1920. Serial No. 396,542.

To all whom it may concern:

Be it known that I, MIKEL SCHULTZ, a citizen of the United States of America, residing at Kaylor, in the county of Armstrong and State of Pennsylvania, have invented certain new and useful Improvements in Double-Moldboard Plows, of which the following is a specification.

This invention relates to certain new and useful improvements in double moldboard plows, or plows of that type which, instead of having landsides, have a second moldboard so that it turns a double furrow, throwing the earth in opposite directions, and particularly serviceable for making surface drains, ridging up, etc.

Many plows have heretofore been made so as to have their double moldboards expand, and they have been adjusted by various mechanical contrivances although regulated with some difficulty. Besides this, the majority of double moldboard plows are commonly provided with such mechanism for expanding the moldboards thereof that they cannot be conveniently expanded and contracted while the plow is running, a great desideratum when the rows of corn are at irregular distances apart in order to cultivate it properly.

By the present improvement, these objections are obviated, first by moving wings of the moldboard only, and, secondly, by an improved mechanism by which the expanding can be effected easily and conveniently while the plow is in motion.

Other objects will appear as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is a side elevational view of a plow constructed in accordance with the present invention,

Fig. 2 is a bottom plan view thereof, with the handles partly broken away,

Fig. 3 is an end view of the device shown in Fig. 2 looking toward the right of the latter and drawn on a larger scale, and

Fig. 4 is a horizontal sectional view taken on line IV—IV of Fig. 3.

Referring more in detail to the several views, the present invention embodies the

usual beam 5 provided with a clevis 6 at its forward end and having handles 7 at its rear end, which handles are preferably of strip metal suitably formed and bolted as 60 at 8 to the beam 5 as well as provided with hand grips 9 at their free ends.

The forward end portion of the beam 5 is provided with a shank 11 of the furrow gage 12.

A combined standard and double stationary moldboard member 19 is rigidly fastened to the beam 5 rearwardly of the furrow gage, said member 19 being provided with an angular extension 20 adapted to be fitted 70 and bolted in a groove of the beam 5 for this purpose as clearly shown by dotted lines in Fig. 1. The lower end of the member 19 is provided with a forward extension 21 having a double plow share and point 22 75 bolted thereon, and a bar 23 has its forward end rigid with the lower end of the member 19 and extends rearwardly to a point beneath the rear end of the beam 5 where the lower ends of the handles 7 are bolted there- 80 to as at 24.

The combined standard and double moldboard member 19 has a pair of movable wings 25 hinged to the rear edges thereof, one on each side and movable inwardly and 85 outwardly toward and away from each other, the hinges 26 of the wings being substantially vertical so that the wings swing substantially on a horizontal plane. For the purpose of practicability and convenience in 90 manufacture, the stationary moldboard members 19', standard 19 and extensions 20 and 21 are preferably formed integral.

An adjusting screw 27 is substantially horizontally disposed beneath the beam 5 95 rearwardly of the member 19 and has its forward end journaled in the latter member as clearly shown at 28 in Fig. 4. The rear end portion of said screw 27 is journaled in a swiveled bearing 29 supported by and between the handles 7 beneath the beam 5. A bevel gear 30 is fastened upon the extreme rear end of the screw 27 and meshes with a similar gear 31 fastened upon the lower end of a vertically disposed shaft 32 which projects through and is journaled in the rear end of the beam 5, a suitable crank or handle 33 being provided upon the upper end of the shaft 32 within convenient reach of the operator of the plow. A nut in the form of 100 a threaded sleeve 34 is threaded upon the screw 27, and each side of said nut 34 is

connected to one of the moldboard wings 25 by means of a link 35, one end of each link being pivoted in an ear 36 of the adjacent wing and in an ear 37 at the adjacent 5 side of the screw 34. It will thus be seen that when the shaft 32 is manually rotated, the screw 27 is also rotated for causing traveling movement of the nut 34 on said screw longitudinally of the latter, forward 10 movement of the nut 34 causing folding of the links 35 for contracting or collapsing the wings 25, and rearward movement of said nut causing expansion of the wings by reason of the straightening of the links 35. 15 The bearing 29 is swiveled so as to prevent any likelihood of binding of the parts of the adjusting mechanism, and as the wings 25 are similar but reversely curved and the connections between the same and the nut 34 20 are identical, it will be seen that similar operative movement of the wings will be caused upon operation of the shaft 32.

The present plow can be contracted and expanded readily while in motion and within 25 sufficient range to take care of any irregularity in running the rows in planting when the plow is used between rows for cultivating. Also, by this means, a great saving in labor and time can be obtained and the 30 work can be more satisfactorily performed for improving crops by means of the present practical construction.

Minor changes may be made without de-

parting from the spirit and scope of the invention as claimed.

35

What is claimed as new is:—

In a double mold board plow of the class described, a horizontal beam, a combined double stationary mold board and standard rigid with and extending downwardly from 40 the intermediate portion of the beam, oppositely curved mold board wings hinged to the rear edges of the combined mold board and standard for a lateral swinging movement, a vertical crank shaft journaled 45 in and extending through the rear end of said beam, a crank handle on the upper end of said crank shaft above the beam, a substantially horizontal screw arranged longitudinally beneath the beam and having its 50 rear end geared to the lower end of said crank shaft, a nut threaded upon said screw and having flexible connections with said wings, said flexible connections each including a link pivoted to the nut and to one adjacent wing, a pair of plow handles secured against the opposite sides of the beam and extending above and below the latter, said screw being journaled at its forward end in the combined mold board and standard, and 55 a swiveled bearing for the rear end portion of said screw carried by and mounted between the lower portions of said handles beneath the beam.

In testimony whereof I affix my signature. 65

MIKEL SCHULTZ.
